UNITED STATES PATENT OFFICE.

HARRY FORD SMITH, OF LEXINGTON, OHIO.

GAS-PRODUCER.

1,098,059.

Specification of Letters Patent. Patented May 26, 1914.

Application filed September 20, 1912. Serial No. 721,417.

To all whom it may concern:

Be it known that I, HARRY F. SMITH, a citizen of the United States, residing at Lexington, in the county of Richland and State 5 of Ohio, have invented certain new and useful Improvements in Gas-Producers, of which the following is a specification.

My invention relates to an improvement in gas producers, and the object is to provide 10 a rectangular casing having a central gas outlet extending in a direction of the greatest dimensions of the casing, with fuel magazines located laterally on either side of the gas outlet, and downwardly converging 15 mechanically operated grates extending on either side parallel to the gas outlet.

The grate bars are pivoted at one end and are actuated by cams, so that the bars are thrown alternately up and back by the action 20 of the cams. In this manner the grate bars act as stokers to force the fuel radially inward toward the center producing an underfeed effect on the fuel, thereby largely destroying the tar, and also serving to break 25 up the coke and eliminating the need of hand firing. When the bars move inward the fuel is forced ahead of the bars toward the center of the producer, and when the bars return, a space is formed between the 30 bars and the fuel bed, which space is partially filled by the fresh fuel from above sliding down along the lining. By this method or process fresh fuel is kept feeding downward onto the lateral grate sections 35 and the fuel is ignited, and partially coked when it is forced inward toward the center of the incandescent fuel bed, and the fresh coal comes into combustion first on these grates, and any coke that may be formed 40 during the initial combustion is broken up into small pieces by the alternate movements of the lateral grate bars. Furthermore, in this manner an underfeed effect is produced whereby a large amount of the tar and volatile 45 matter in the coal is consumed.

The invention consists of certain novel features of construction and combinations of parts which will be hereinafter set forth and more particularly pointed out in the claims.

50 In the accompanying drawings Figure 1 is a top plan view, with a portion of the casing broken away to show the interior construction; Fig. 2 is a longitudinal vertical sectional view through the ash pits; Fig. 3 is an end view; Figs. 4 and 5 are en-

larged detail sectional views of the grate bars.

A represents the rectangular casing of the producer, and 1 is the top. The casing is mounted on the wall 2 of the ash pits B, B. 60 Located through the center of the producer and mounted on suitable supports or rails 4 are a series of sections of the usual or ordinary rocking grates 5, 5. Extending longitudinally of the producer are two 65 shafts 6, 6 which are located on each side of the shaking grate sections 5. Mounted on the shafts 6 are grate bars 7, 7 which extend along the side walls of the producer, and the upper ends of the bars received in a recess 8 70 formed in the walls of the casing, but the bars remain in a position so that their uppermost ends are in a line with the wall of the producer. Mounted in rear of the grate bars 7 on each side of the producer is a cam 75 shaft 9 upon which shaft cams are mounted. The cams are so located on each shaft that they will be brought into engagement with the grate bars for causing the grate bars on each side of the producer to be alternately 80 operated. U-shaped brackets 10 are formed on the grate bars 7, and extend over the shafts 6 for supporting the bars on the shafts. A rack bar 11 is provided for fastening the grate bars to the shafts 6 85 against lateral movement.

The ash pits are arranged in sections, that is for each section of grates an independent ash pit B is formed. Connecting the walls 90 2 are a plurality of partitions 12 upon which are mounted the rails 4 for supporting the ends of the grate sections 5. The walls of the ash pits taper downward to an opening 13 formed in the bottom of the pits through which the ash can be discharged. The upper end or mouth of the ash pits are of greater width than the grates 5 so that any ash passing through the grates 7 will enter 95 the pits. At the ends of the grates a steel plate C is located which extends upwardly to the brick lining D of the producer for completely separating the ash pits into 100 separate divisions.

Extending longitudinally of the producer 105 is a blast pipe E to which is connected a pipe G for each ash pit. The pipe G extends through the wall 2 and into the pit, and a valve 14 is provided for each pipe G so that the amount of air to be delivered to the 110 respective pits can be regulated to suit the

requirements. In some instances one grate section will require more air blast than another, and by the provision of independent ash pits for each grate section the amount of air necessary for the respective grate sections can be controlled. A bell-crank lever 15 is connected to each valve 14, and a rod 16 is connected to each lever 15 which rod extends through the wall 2 in position to be grasped by the operator. The valve or hood 14 which is applied to each branch pipe G prevents any ash from falling into the pipe G when the hood is closed or in a raised position, the valve being preferably constructed cone-shaped and fitting well over the end of the opening in the pipe.

The ends 17 of a Pitot tube 18 extend into the branch pipes G, and the reading of the tube is indicated by a gage H. One gage 20 and tube is fitted to each branch blast pipe and by reading the various gages it is possible to determine when the rate of flow of blast to each pipe is the same as that to every other section. If it is found that one 25 section is taking more air than the rest as would be indicated by a higher reading on the gage H, the valve 14 can be lowered by the rod 16 until the blast to each section is exactly the same. Dampers 19 are provided 30 for each opening 13 of the ash pits B to prevent the discharge of air through the bottom of the ash pits. A U-shaped hollow trough 20 extends the length of the producer for forming an outlet for the gas, and located 35 on each side of the trough are lateral fuel magazines 21, 21.

The fresh fuel is fed from the magazines down onto the downwardly converging grate bars 7, from which it is fed to the center of 40 the producer onto the shaking grate sections 5, after the fuel has been first combusted on the grate bars 7, and any coke that may be formed during the initial combustion is broken up into small pieces by the alternate 45 motions of the lateral grate bars 7. The grate bars 7 can be made as wide or narrow as the character of the fuel would seem to require. The bars are alternately oscillated by the cams causing the grate bars to act as 50 stokers to force the fuel radially inward toward the center and producing an underfeed effect on the fuel thereby largely destroying the tar, and also breaking up the coke and eliminating the need for hand firing. It 55 has been found unnecessary to bar the fire as the fuel settles regularly and in approximately the manner indicated; that is, the fresh fuel falling on the grate bars as they return to their normal or rearmost position 60 after forcing the fresh fuel inward after it has been initially combusted on the grate bars. With the aid of the mechanically agitated grate bars it is possible to extend this same principle to the largest size of producer, and to avoid the production of tar.

It will be seen that from the foregoing it is possible to construct a producer of any size, by simply enlarging the casing and adding additional grate bars, and the central grate sections. Compressed air cylinders 22 are located along the walls of the producer 70 for actuating the rocking grates 5 by means of horizontal bars 23 which are connected to the lower terminals of the grate sections and to the compressed air cylinders.

It is to be noted that one of the chief difficulties previously encountered in producers of very large unit size, and also in the operation of several producer units in multiple, has been from the difficulty encountered in 80 keeping each section working at its proper proportion of the load. It is impossible to keep the fuel bed conditions in all exactly the same, and there is consequently a tendency for the load to shift from those sections where the fuel is packed tightly toward those in which the fuel is loose and porous. The construction shown is important in providing practical means whereby this may be readily detected and controlled.

I claim—

1. A gas producer comprising a rectangular casing having a central gas outlet extending across the upper part of the producer in the direction of its greatest dimensions, fuel magazines located laterally on either side of the gas outlet, and downwardly converging mechanically operated grates extending on either side parallel to the gas outlet.

2. A gas producer comprising a rectangular casing having a central gas outlet extending across the upper part of the producer in the direction of its greatest dimensions, fuel magazines located laterally on either side of the gas outlet, grate bars adapted to receive the fresh fuel from the magazines, and means for oscillating the grate bars for causing them to force the initially combusted fuel toward the center of the producer on their inward movement and to receive the fresh fuel on their return movement.

3. A gas producer comprising a rectangular casing, having a central gas outlet extending across the upper part of the producer in the direction of its greatest dimension, fuel magazines located laterally on either side of the gas outlet, downwardly converging mechanically operated grates extending on either side parallel to the gas outlet, and a separate ash pit for each grate section.

4. A gas producer comprising a rectangular casing having a central gas outlet extending across the upper part of the producer in the direction of its greatest dimension, fuel magazines located laterally on either side of the gas outlet, downwardly converging mechanically operated grates extending on either side parallel to the gas outlet, a sep-

arate ash pit for each grate section, and means in each ash pit for supplying and regulating the blast of air to the grate section above said ash pit.

5. A gas producer comprising a rectangular casing having a central gas outlet extending across the upper part of the producer in the direction of its greatest dimension, fuel magazines located laterally on either side of the gas outlet, grate bars adapted to receive the fresh fuel from the magazines, means for oscillating the grate bars for causing them to force the initially combusted fuel toward the center of the producer on their inward movement and to receive the fresh fuel on their return movement, and a separate ash pit for each grate section.

15. A gas producer comprising a rectangular casing having a central gas outlet ex-

tending across the upper part of the producer in the direction of its greatest dimension, fuel magazines located laterally on either side of the gas outlet, grate bars adapted to receive the fresh fuel from the 25 magazines, means for oscillating the grate bars for causing them to force the initially combusted fuel toward the center of the producer on their inward movement and to receive the fresh fuel on their return movement, a separate ash pit for each grate section, and means in each ash pit for supplying and regulating the blast of air to the grate section above said ash pit.

20. In testimony whereof I affix my signature in the presence of two witnesses.
